UNITED STATES PATENT OFFICE.

CARTER J. JOHNSON, OF GREEN BAY, WISCONSIN.

WIRE TIGHTENER FOR CONCRETE FORMS.

Application filed January 10, 1921, Serial No. 436,166. Renewed May 19, 1922. Serial No 562,264.

To all whom it may concern:

Be it known that I, CARTER J. JOHNSON, a citizen of the United States, residing at Green Bay, in the county of Brown, State 5 of Wisconsin, have invented certain new and useful Improvements in Wire Tighteners for Concrete Forms; and I do hereby declare the following to be a full, clear, and exact description of the invention, such as will 10 enable others skilled in the art to which it appertains to make and use the same.

This invention relates to new and useful improvements in wire twisters and tighteners, and particularly to devices or tighteners 15 for use in connection with concrete molding forms.

One object of the invention is to provide a device with which the transverse binding wires of a concrete molding form can be 20 easily and quickly reached and properly twisted, for the purpose of holding the walls of the form together.

Another object is to provide a device of this character by means of which the wires 25 can be twisted in either direction, untwisted, or the device rendered inoperative by a novel means on the handle of the tool.

Other objects and advantages will be apparent from the following description when 30 taken in connection with the accompanying drawing.

In the drawing:

Figure 1 is an elevation of the twisting tool, in operative position within a mold 35 form and engaged with the wires to be twisted.

Figure 2 is an elevation of the tool viewed from a direction at right angles to that of Figure 1.

Figure 3 is an elevation of the device, one side of the casing being removed and the stem above the casing partly in section.

Figure 4 is a vertical longitudinal central 45 sectional view through the device on the line 4—4 of Figure 3, the ratchet wheels in the handle being shown in elevation.

Referring particularly to the accompanying drawing 10 represents a casing having the removable front and back cover plates 50 11 and 12, and having the circular opening 13 in the central portion of its upper wall. In the lower portion of the casing there is mounted a ring 14, the same having an opening 15 in its outer side. In this ring is rotatably supported the gear ring 16, said ring 55 also having an opening 17 in one side for

registration with the opening 15 to admit the wires 18 to be twisted. Formed integral- 60 ly with the gear 16, at a point diametrically opposite to the opening 17, and projecting across the center of the ring toward the opening 17, is a pin or tongue 19, which is engaged between the wires 18, when said wires are passed through the openings 15 and 17, into the interior of the ring gear 16. 65 The inner face of the ring 14, that is the wall of the central opening thereof, is formed with a channel 20 in which are disposed the bearing rollers 21, and on these bearings the hub of the gear ring 16 rotates. The periph- 70 ery of the gear ring is formed with teeth 16' which are meshed by the teeth of the two gears 22 mounted on shafts 23 which extend across the casing. A shaft 24 is dis- 75 posed transversely in the casing above and intermediate the shafts 23, and on this shaft there are mounted the bevel gear 25 and the plain gear 26. The plain gear 26 meshes with both of the gears 22 simultaneously, as clearly seen in the drawing for the purpose 80 of driving the gear ring 16.

Disposed within the opening 13, and ex- 85 tends therefrom above the casing, is a tubular member 27, and rotatably disposed in the lower portion of said tubular mem- 90 ber, and projecting into the casing, is a rotatable member 28, a bevel gear 29 being secured on the lower end of the tube and meshing with the before-mentioned bevel gear 25 of the shaft 24. The member 95 28 is formed with a peripheral groove 28' in which is disposed the inner end of a screw 30 carried by the member 27, whereby the tube or member 27 and the member 28 are capable of independent rotation. Ex- 100 tending upward from the center of the member 28 is a stem 31 of angular cross section, and on this stem are disposed the ratchet wheels 32, 33, and 34, and the re- 105 duced stem 35' of the member 28. On one side of the tube 27 there is mounted a longitudinally extending casing 36 having a longi- 110 tudinal slot 37 in its outer wall, and dis- posed through this slot is the stem 38 of the detent 39, the detent also being disposed in an elongated slot in the side of the tube. A coil spring 40 is disposed on the stem 38, between the outer wall of the casing 36 and the head of the detent, said spring normally urging the detent inwardly into 115 engagement with one or another of the ratchet wheels. The teeth of the wheel 32

extend in a direction to permit the detent to engage therewith when the tube 27 is turned toward the right and to ratchet idly thereover when the tube is rotated in the 5 opposite direction. The wheel 33 is formed to permit the detent to grip therewith when the tube is turned toward the left, while the wheel 34 has its teeth so formed as to prevent rotation of the tube in either direction. 10 When the detent is opposite the stem 35, the tube may be rotated in either direction. It will thus be seen that when the detent is 15 in engagement with any of the ratchet wheels the tubular member 27 and the member 28 are locked together for simultaneous rotation.

Secured to the upper end of the stem 31 is a handle 27', the lower end portion of which is reduced and disposed within the 20 upper end of the tubular member 27.

The wire 18 having been properly passed back and forth through the side walls of the mold form, and the ends twisted outwardly of the said sides, there extend two 25 strands across the space between the sides. It is these two strands which are adapted to be twisted by the tool above described, whereby the wire is properly stretched and the sides of the form held in proper position. The handle of the tool is rotated to 30 rotate the gear ring 16 so as to register its side opening 17 with the opening 15 of the ring 14, when the tool is passed between the sides of the mold until the wire strands 35 pass through the said openings 15 and 17, and the tongue 19 disposes itself between the strands. Then upon rotating the handle so as to rotate the tubular member 27, the gearing will turn the gear ring 16, rotating the wire strands therein and twisting 40 them about each other until the required tension has been obtained.

By shifting the detent from one ratchet wheel to another, the operator may cause 45 the twisting of the wires in either direction, or may untwist them.

The common method employed to accomplish this twisting of the wire strands consists in inserting a nail or spike between 50 the strands and then rotating the nail or spike. This has proven unsatisfactory as the spike or nail often slips from the grasp of the operator, entailing loss of time and patience. The present device possesses considerably more leverage and power than the 55 employment of a nail or spike, with the consequent expenditure of less time and labor.

What is claimed is:

60 1. A wire twisting tool comprising a casting having a ring in one end formed with an opening in the lower side thereof for the

entrance of the strands of wire to be twisted, a rotatable ring gear mounted in the said ring and having an opening in one side for 65 registry with the opening of the first ring to receive said wire strands, a pair of gears meshing with the ring gear, a common gear meshing with said pair of gears and mounted on a shaft in the casing, a bevel gear on the 70 shaft, and a rotatable ratchet means in the casing and carrying a bevel gear meshing with the first bevel gear.

2. A wire twisting tool comprising a stationary ring having an opening in one side, 75 a rotatable ring mounted within the stationary ring and having an opening in one side adapted for intermittent registration with the opening of the stationary ring, a rotatable tube carried by the casing of the tool, 80 a gear on the tube operatively engaged with the ring gear, a stationary member within the tube, a series of ratchet toothed members on the stationary member, and a detent on the tube shiftable into engagement with the 85 individual ratchet toothed members.

3. A wire twisting tool comprising a stationary open ring, a rotatable open ring mounted within the stationary ring, a handle connected with the stationary ring and including a pair of relatively rotatable members, one of the members being operatively connected with the rotatable ring, and means carried by the other member and shiftable into engagement with the first member for 90 producing unitary rotation of both members.

4. A wire twisting tool comprising a stationary open ring, a rotatable open ring mounted in the stationary ring, a handle connected with the stationary ring and including a rotatable tube, a driving element fixed on the tube and operatively engaged with the rotatable ring, a rotatable stem within the tube and carrying toothed elements, and 100 a detent on the tube shiftable from one to another of the toothed elements for clutching the tube and stem together.

5. A wire twisting tool comprising a stationary ring and a rotatable ring, a pair of 110 relatively rotatable members one of which is in driving engagement with the rotatable ring, the other member having a plurality of toothed elements, and a shiftable detent carried by the first member for clutching engagement with the different toothed elements to permit the members to be simultaneously rotated in either direction.

In testimony whereof, I affix my signature, in the presence of two witnesses.
